CLAIM

The ornamental design for a control handle of an endoscope device, as shown and described.

DESCRIPTION

FIG. 1 is a front perspective view of a control handle of an endoscope device, according to the novel design.

FIG. 2 is a rear perspective view thereof.

FIG. 3 is a bottom perspective view thereof.

FIG. 4 is a right plan view thereof.

FIG. 5 is a front plan view thereof.

FIG. 6 is a left side plan view thereof.

FIG. 7 is a right side plan view thereof.

FIG. 8 is a top plan view thereof; and,

FIG. 9 is a bottom plan view thereof.

The dashed lines in FIGS. 1-9 represent unclaimed portions of the control handle for an endoscope device and form no part of the claimed design.
